UNITED STATES PATENT OFFICE.

HAYMAN FREEDMAN, OF ROCHESTER, NEW YORK, ASSIGNOR OF ONE-HALF
TO NATHAN STEIN, OF SAME PLACE.

TUCKING-GUIDE FOR SEWING-MACHINES.

SPECIFICATION forming part of Letters Patent No. 393,329, dated November 20, 1888.

Application filed January 15, 1887. Serial No. 224,485. (No model.)

To all whom it may concern:

Be it known that I, HAYMAN FREEDMAN, of the city of Rochester, in the county of Monroe and State of New York, have invented 5 a certain new and useful Improvement in Tucking-Guides for Sewing-Machines; and I do hereby declare that the following is a full, clear, and exact description of the same, reference being had to the drawings accompanying 10 this application.

This invention relates to an attachment for tucking thick and heavy goods—such as woolen cloths—which are made up into children's garments, and is especially for use in 15 children's clothing manufactories. It is found that the ordinary plaiters—such as accompany common sewing-machines for plaiting light goods—will not answer this purpose; hence it is the practice in clothing-manufactories to do 20 the work by hand, first marking the tucks with a measure, then folding and basting the tucks, and finally stitching, each operation being complete in itself.

It is the object of my invention to obviate 25 these difficulties by producing a device by which the work can be done on a more expeditious, effective, and accurate manner.

In the drawings, Figure 1 is a plan view of the tucking attachment located in the bed plate 30 of a sewing-machine, showing also a cross-section of the needle-bar and presser-foot. Fig. 2 is a side elevation of Fig. 1 looking in the direction of arrow 1, Fig. 1. Fig. 3 is a longitudinal section in line $x-x$, Fig. 1. Fig. 4 is a 35 rear elevation of Fig. 1, enlarged, looking in the direction of arrow 2, Fig. 1.

A indicates the body of the device, the same consisting of a metal strap or plates provided at its left-hand end with a vertical flange, a , 40 that forms a guide, and also provided with a longitudinal slot, b , for the attachment of the gage-bar and attaching-bar, as will presently be described. The top surface of the plate A is laid out in a scale of inches and subdivisions, as shown,

B is a gage-bar, and C an attaching-bar, both standing at right angles to the plate A, and secured thereto, on the under side by screws, on which are screw clamping-nuts $d-d$. These 50 bars are adjustable laterally on the plate A to any desired position by simply loosening the

nuts. The attaching-bar C is provided with a series of holes, $c-c$, through any of which passes a thumb-screw, f , to attach the bar fast to the bed E of the sewing-machine, which is 55 always provided with a hole to receive the screw. This hole in the bed is at different places in different machines, and the object of the holes in the attaching-bar, and also of the lateral adjustment of said bar on the plate A, 60 is to fit the said bar to the different positions of the hole in the plate, and also to bring the flange a in proper relative position with the needle G and presser-foot H. The object of adjusting the gage-bar B laterally is to produce 65 different widths of tucks, as will presently be described. The square edge of the gage-bar next to the needle serves as the shoulder or guide for the folded edge of the cloth to run against.

The operation is as follows: The left-hand edge of the cloth is first folded over, and then stitched up simply to form a rib, j , as the starting-point of the tucking. This rib is placed outside of and against the vertical 70 guide-flange a of the tucker. The gage-bar B is then moved inward or away from the needle a distance equal to the desired width of the tucks previously determined on. The loose end of the cloth is then doubled under and 75 turned back toward the left, which makes a fold in the cloth. In this condition the cloth is run through the sewing-machine, the rib j , previously formed, running against the flange a , and the loose folded edge of the cloth running 80 against the edge of the gage-bar B. The needle passes through the double folds of cloth intermediately between the rib and the folded edge, as shown. This forms the tuck, which is then turned up and is moved 85 outward, and forms the rib that runs against the flange a in forming the second tuck. In this manner the tucks are all formed in 90 succession, one after another, working from the left to the right of the cloth. In ordinary tucking attachments now in use the 95 tucks are made working from the right to the left. Very thick and heavy goods can be plaited by this attachment, which cannot be done by ordinary tuckers used with sewing- 100 machines.

In very heavy goods it is necessary to hold

the folded edge down in advance of the plate A, and opposite to the needle and presser-bar, so that the fold will keep in contact with the edge of the gage-bar B; otherwise the cloth 5 will spring up at that point and lose its hold against the gage-bar. I employ for this purpose a spring, M, provided with a slot, s, by which it can be clamped and held by the thumb-screw f. The end t of this spring 10 rests on the point of the presser-foot, so that it will rise and fall with the presser-foot to allow the cloth to be fed along, and the spring is provided below the end t with a bearing-end, v, that bears on top of the cloth and 15 holds it down at the point opposite the needle, so that it cannot rise above the edge of the gage-bar B. If desired, a shorter re-enforcing spring, N, may be used resting on top of the spring M.

20 What I claim as new is—

In a tucking attachment for sewing-machines, the combination of the plate A, provided with a guide-flange, a, resting outside of the needle, a gage-bar, B, attached to the plate resting inside of the needle, an attaching-bar, C, provided with a series of holes to attach the device to a sewing-machine bed by a set-screw, and a spring, M, attached at one end to the attaching-bar, the other end resting on the presser-foot and provided with a projection, v, that bears on the cloth next to the needle, as shown and described, and for the purpose specified. 25

In witness whereof I have hereunto signed my name in the presence of two subscribing 30 witnesses.

HAYMAN FREEDMAN.

Witnesses:

NATHAN STEIN,
R. F. OSGOOD.
